ART OF REFRIGERATION

Original application filed August 9, 1920, Serial No. 402,403. Divided and this application filed November 17, 1925. Serial No. 69,624.

My invention relates to improvements in the art of refrigeration and particularly to the compression method of refrigeration in which is employed the evaporation of liquids 5 to effect the heat flow. In this method the refrigerating liquid such as sulphur dioxide, ammonia, carbonic acid or the like at a given temperature and corresponding pressure flows into a lower pressure and corresponding 10 temperature, evaporation takes place at this temperature, the required heat being drawn from the liquid or refrigerant and the cooling body, thus lowering their temperatures. The vapor formed is then compressed and condensed at the original pressure and temperature, the heat being absorbed 15 by a cooling fluid. The cycle thus reveals a closed circuit of refrigerating liquid and vapor in contact but not mixed, one section 20 of which is kept at a high pressure, and the other at a low pressure accompanied by two heat currents at different thermal levels and in opposite directions, i. e. at the lower level the heat current passes into the refrigerating 25 liquid and at the higher pressure the heat current passes from it, all of which is in conformity with the recognized laws of thermodynamics.

Though rotary compressors have been proposed the compression in the cycle has heretofore, to my knowledge, been accomplished only with reciprocating compressors of various types possessing the complications and objections inherent in devices of this character. The expansion has generally been through orifices or cocks which divides the circuit and direct from the high to the low pressure sections, thus losing the external 35 energy possessed by the expanding vapor.

The object of my invention is to eliminate the compressor expansion cock and divided circuit to save the energy of the expanded vapor thus producing the carnot cycle, and 40 to attain the desired effect by gradually producing the required variation of pressure and temperature in an undivided closed circuit of refrigerating liquid and vapor (which thus itself performs the compressing function) enclosed in a conduit free from valves,

expansion cocks and compressors. I attain this object by the form of my device illustrated in the accompanying drawing but modifications may be made therein without departing from the spirit of my invention. 55

This application is a divisional application of my application, on which there was issued to me Letters Patent No. 1,565,795, dated December 15, 1925.

The preferred form of my device is illustrated in the accompanying drawing, in which

The figure is a diagrammatic view of the device.

Similar characters of reference refer to similar parts in the specification and drawing.

In the device here illustrated, I present a method of applying to the art of refrigeration the theorem that in a continuous conduit 70 through which liquid and vapor is flowing adiabatically the sum of the heat energy and kinetic energy at every section is constant, in other words, variation of pressure and temperature may exist of a magnitude corresponding to variations in velocity which in turn can be produced by variation in the area of successive cross sections of the conduit. As is obvious, the conduit may be a closed circuit without affecting this law, and if energy be introduced in the conduit sufficient to overcome frictional resistances plus the energy equivalent to the net work of adiabatic compression the circulation becomes continuous and it is apparent that if low 85 temperature heat is absorbed at the low pressure point of the circuit and if it, plus the heat of adiabatic compression and friction and other heat added is discharged at the high pressure point a refrigerating cycle of the compression type results.

Particularly I make application of the hydraulic principles that the pressure in a column of liquid varies directly with the height of the column; and that if the velocity of the flow in the column is sufficiently high, any vapor formed will be entrained by the liquid and subjected to its hydraulic pressure existing at each level in the column or riser.

In the drawing 1 and 2 are the risers which

need not be of constant diameter, 3 is the brine cooler, or source of low temperature heat, and 4 is a condenser of any desired type. A pump 5 is provided in the system. It is obvious that any desired hydraulic pressure can be attained in the condenser 4 by extending the height of the risers 1 and 2 and must at least equal the difference between condenser and brine cooler pressures, also that the hydraulic pressure at the brine cooler 3 will be zero. The circuit is filled with refrigerating liquid or medium to a point where there is left only sufficient space to permit evaporation. Any desired type of brine cooler 3 and condenser 4 may be used. The circulation of the refrigerating liquid or medium is maintained by means of the pump 5.

The shaded sections *a*, *a*, diagrammatically illustrate the increase and decrease of vapor in suspension with the consequent changes in the temperatures and pressures accompanying adiabatic expansion and compression and the reception rejection of heat.

The circuit can be divided into two parts or legs, the expansion riser 1 from condenser to cooler in the direction of the flow, and the compression riser 2 from cooler to the condenser in the same direction. If no heat was added or subtracted from the system it is apparent that, neglecting friction, the refrigerating medium once set in motion, would continue to circulate indefinitely exhibiting the changes of temperature and pressure above described, and the decreasing scales of pressure and temperature in riser 1 would be duplicated in inverse order in riser 2, the net result being a perfect hydraulic and vapor tension balance. The heat supplied from the cooler 3 however, disturbs this balance and the quantity of heat in transit in riser 2 as well as the vapor in suspension becomes proportionately greater, the effect of which is to reduce the mean density of the refrigerating medium in said riser, and consequently by the columns no longer balance. In order then to maintain the circulation, energy must be supplied which is the function of the circulating pump 5. The energy thus supplied is that necessary to compress the additional vapor generated by the cooler 3 and after traversing the condenser the circuit is thus restored to its original state.

The fundamental principle of this method consists broadly in setting up various pressures in an integral body of refrigerating liquid in motion, supplying low temperature heat to the system at the points of low pressure and withdrawing high temperature heat at points of high pressure, the liquid serving as a transporting agent to move the vapor thus formed from point to point and to compress it all in exact accordance with the theoretical compression refrigeration cycle. In my system the heat transfer surfaces, the hydraulic heads in the risers and the pressures

and the brine temperature the cooling water, and the refrigerating liquor circulation will all be so proportioned to the quantity of low temperature heat supplied and its temperature, that the refrigerating liquid leaving the condenser will be entirely free from vapor in suspension, at or below the temperature corresponding to the maximum pressure in the system, in other words, the heat in the liquid leaving the condenser will be in the sensible form only. As the liquid passes on, the pressure grows less and vapor will form, withdrawing heat from the liquid in the latent form in sufficient quantity to make pressures and temperatures conform arriving at the brine cooler with minimum pressure and corresponding temperature, heat will be received at constant temperature accompanied by a proportionate formation of vapor indicated at *a*, *a*, containing latent heat in quantity to balance that received. As the liquid passes on it enters the zones of increasing pressure with this added quantity of vapor in suspension which gradually condenses and is completely condensed in the condenser 4.

Having thus described my invention, what I claim is:

1. In a device of the character described, the combination of a closed valveless circulating system, including a pair of risers adapted to set up static pressures in a refrigerant therein by gravity alone and constituting compressor means in said system, a cooler operatively connected in said system and a condenser also operatively connected in said system.

2. In a refrigerating system, a conduit having compressor means comprising vertical risers of substantially equal length adapted by gravity alone to set up operative static pressures in a refrigerant contained therein, connecting conduits between said risers respectively at the tops and bottoms thereof, a refrigerant medium in said conduit, a cooler to impart heat to said refrigerant medium in operative relation to one of said connecting conduits, a condenser to abstract heat from said refrigerant medium at the other of said connecting conduits, and means to circulate said refrigerant medium through said conduit.

3. In a refrigerating system of the character described, a conduit of uniform cross-sectional area having vertical risers of substantially equal length and having connecting conduits between said risers respectively at the tops and bottoms thereof, a refrigerant medium in said conduit, a cooler to impart heat to said refrigerant medium at the upper of said connecting conduits and between said risers, a condenser to abstract heat from said refrigerant medium at the lower of said connecting conduits, and a pump at the junction of one of said risers and the lower connecting conduit.

4. In a refrigerating machine, and endless closed conduit, a refrigerant circulating therein and comprising a mixture of liquid refrigerant and its vapor, a high pressure zone and a low pressure zone in the refrigerant produced by gravitational force alone, and a pump by which the refrigerant is circulated.

5. In a refrigerating apparatus, an endless closed conduit having two riser sections adapted by their height to operatively produce in a refrigerant contained therein zones of unequal static pressures, a refrigerant medium in the conduit, means for circulating the refrigerant medium, and a cooler and a condenser in combination.

6. In a compression refrigeration closed system, the combination of an evaporator, a condenser, a pump, and a connecting conduit including uptake and downtake risers of sufficient height that when filled with a mixture of liquid and vapor refrigerant in motion a hydrostatic pressure will be produced therein at the condenser, greater than the difference between its pressure and that in the evaporator.

7. In a refrigerating system, the combination of compressor means comprising a pair of substantially vertical risers of equal height, adapted by gravity alone to set up operative static pressures in a refrigerant contained therein, conduits between said risers whereby refrigerant may circulate through said risers and said conduits, a refrigerant medium in said risers and said conduits, and means to cause said refrigerant to circulate and means for adding heat to the refrigerant.

8. In a refrigerating system the combination of compressor means comprising a pair of risers adapted by gravity alone to set up operative static pressures in a refrigerant contained therein, conduits between said risers whereby refrigerant may circulate, a refrigerant medium in said risers and said conduits, means to circulate said refrigerant, a cooler in said system for adding heat to said refrigerant at a point of substantially zero pressure, and a condenser in said system for cooling said refrigerant.

In testimony whereof I affix my signature.
BARTON H. COFFEY.
